(57) **CLAIM**

The ornamental design a dispensing bottle cap, as shown and described.

DESCRIPTION

FIG. 1 is a perspective view of a first embodiment of a dispensing bottle cap according to the present invention.

FIG. 2 is an elevation view thereof.

FIG. 3 is a top plan view thereof.

FIG. 4 is a bottom plan view thereof.

FIG. 5 is a perspective view of a second embodiment of a dispensing bottle cap according to the present invention.

FIG. 6 is an elevation view thereof.

FIG. 7 is a top plan view thereof.

FIG. 8 is a bottom plan view thereof.

FIG. 9 is a perspective view of a third embodiment of a dispensing bottle cap according to the present invention.

FIG. 10 is an elevation view thereof.

FIG. 11 is a top plan view thereof.

FIG. 12 is a bottom plan view thereof.

FIG. 13 is a perspective view of a fourth embodiment of a dispensing bottle cap according to the present invention.

FIG. 14 is an elevation view thereof.

FIG. 15 is a top plan view thereof; and,

FIG. 16 is a bottom plan view thereof.

(Continued)

The broken lines show portions of the dispensing bottle cap that form no part of the claimed design.
